Primary Examiner — Richard E Chilcot*(74) Attorney, Agent, or Firm* — The Webb Law Firm(57) **CLAIM**

The ornamental design for a wheel loader, as shown and described.

DESCRIPTION

1. Wheel loader
 1.1 : Front
 1.2 : Back
 1.3 : Left
 1.4 : Right
 1.5 : Top
 1.6 : Perspective
 1.7 : Perspective

1 Claim, 7 Drawing Sheets(56)
